(57) **CLAIM**

The ornamental design for a powered brush handle, as shown and described.

DESCRIPTION

FIG. 1 is a top front right perspective view of a powered brush handle, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines immediately adjacent the shaded areas represent the bounds of the claimed design while all other broken lines are included for the purpose of illustrating portions of the powered brush handle; the broken lines form no part of the claimed design.

1 Claim, 6 Drawing Sheets*Fig. 1.*
